UNITED STATES PATENT OFFICE.

DEAN A. HOLZBERG, OF SAN JOSE, CALIFORNIA, ASSIGNOR OF ONE-HALF
TO FRANK CHEEK, OF SAN JOSE, CALIFORNIA.

STREET AND STATION INDICATOR.

No. 813,895.

Specification of Letters Patent.

Patented Feb. 27, 1906.

Application filed January 25, 1905. Serial No. 242,646.

To all whom it may concern:

Be it known that I, DEAN A. HOLZBERG, a citizen of the United States, residing at San Jose, in the county of Santa Clara and State 5 of California, have invented new and useful Improvements in Street and Station Indicators, of which the following is a specification.

My invention relates to an apparatus 10 which is designed to indicate streets, stations, or other points, so that passengers within a car or vehicle may be informed of the position of the car from time to time.

It consists in the combination and arrangement of parts and in details of construction, 15 which will be more fully explained by reference to the accompanying drawings, in which—

Figure 1 is a front elevation of my indicator with cover removed. Fig. 2 is a sectional plan view of same. Fig. 3 is a section of disk, showing method of removing cards. Fig. 4 is a partial section of box, showing stops for cards. Fig. 5 is a transverse section through end of box, showing mechanism, but with cards removed. Fig. 6 is a side elevation of contact device. Fig. 7 is an end elevation of same. Fig. 8 is a section through cover, showing spring-stop and 30 roller.

For convenience of passengers in case of cars which are alternately run with one end or the other forward, as where cars are not turned at the end of the run, I have designed 35 to employ two of my devices, one being located at each end of the car.

As shown in the drawings, A is a suitable casing having an open front, which is preferably protected by glass or other transparent 40 covering. Within this casing is fixed a suitable framework or standards 2, and these support the journals of a horizontal shaft upon the ends of which are mounted disks 3 and 4. Near the periphery of these disks are 45 made small holes, which are adapted to receive the pins 5 of the leaves or plates 6. These leaves or plates are sufficiently rigid and have a surface upon which the required names may be plainly shown. The leaves 50 have their pivots near one edge, so that when released they may fall by gravitation and hang from these pivots.

The disks may be of any suitable diameter adapted to carry as many of the indicating-

leaves as may be required for the length of 55 the run. Thus if employed in a street-car there would be one of these leaves for each street or point which it is desired to indicate. In the normal position of the apparatus those leaves which are below the center of the disks 60 will normally hang in vertical planes, and as the disks are revolved, so that the leaves are carried up on the rear side, they will gradually fall and lie against each other until they reach a point near the front, where they pass 65 the vertical plane, when they will fall forward. The leaves that thus fall forward contact against arms or stops 6^a, which are here shown as fixed to the upper part of the case. In this position the back of a leaf which is 70 thus held will be shown, and upon this back may be placed advertising or other matter, if desired. As soon as the leaf passes the retaining-stops it will drop by gravitation and hang in a vertical position, so that the 75 opposite side of the leaf will be exposed, and upon this is marked the street or other information which it is designed to give. In order to revolve this carrier and the leaves pivoted therein, the shaft upon which the carrier is supported is extended sufficiently and has fixed to its end a pinion 7. This pinion is engaged by a gear-wheel 8, the shaft of 80 which is also journaled in the standards. 85

In conjunction with the gear-wheel is a cylindrical shell 9, containing a spring one end of which is fixed to the shell and the other to the shaft, which is loosely turnable within the shell and gear. By means of a pawl and ratchet, as at 10, the shaft is held at any desired point when the spring has been wound up, so that the tension of the spring acts between the stationary shaft and the interior of 90 the drum, the tendency being to turn the drum whenever released, and through it the 95 gear and pinion to turn the carrier.

The spring may be wound up from time to time by means of a crank or equivalent turning device adapted to engage the end of the shaft and to turn it until the spring has been 100 wound, when the pawl and ratchet at 10 will hold it in that position.

In order to allow the carrier to be turned by the action of the spring, one of the disks, as 3, has teeth formed upon or carried by it, 105 as shown at 3^a, and these are engaged by a double-acting pawl 11, fixed to a journal-shaft 12, as shown. Upon this shaft is mount-

ed an arm 13, one end of which carries an armature 14, and the other end is connected with a spring or springs, as at 15, by which it is normally drawn down, and the armature is raised so that it is out of contact with the poles of the electromagnet 16. When this electromagnet is energized, the armature will be drawn down to the poles and the shaft carrying the double pawl will be rotated, so as to 5 tilt the pawl sufficiently to release one of the teeth 3^a and allow the carrier to be moved forward by the action of the previously-described spring. The other end of the pawl simultaneously engages a tooth of the carrier- 10 disk to prevent its advancing more than one tooth, and this advance is sufficient to release one of the leaves from the stops which hold it up. As the leaf passes the stops it drops, as 15 before described, swinging into a position 20 which will expose the name of the street or other desired information.

The amount of movement of the armature is regulated by means of an adjusting-screw, as at 17, against which the rear end of the armature-carrying arm contacts when the armature is attracted, and the tension of the spring may be similarly regulated. Below the screw 17 is a screw 17', having a pin around which is coiled a spring 17². By turning the screw 17' the pin is lowered or raised, thus increasing or decreasing the distance between the end of the pin and the point of the screw 17 and the consequent amplitude of vibration of the armature.

35. In order to energize the armature at the proper time, this device being applied to electrically-operated cars, I have shown the following structure: At a suitable point on the electrical conductor which furnishes power to 40 the motor of the car is fixed one member of a tact device, and that part of the car through which the current is carried to the motor carries the other member of this contact device. These devices are fixed at any 45 desired point with relation to the street or point to be indicated, so that when the car reaches this point the circuit will be completed, and the current momentarily passing through the contact device will be passed 50 through the electromagnet and energize it to move the carrier and expose another leaf. This mechanism will be varied to suit the character of the conductor. Thus it may be applied to a third-rail apparatus or to an 55 overhead trolley.

For purposes of illustration I have here shown the apparatus as operated by means of an overhead trolley. The trolley-wire has suspended from it by any suitable means an 60 arm or shoe 18, which stands lengthwise and parallel with the direction of the wire. The trolley-pole 19, which is illustrated in the present case, has fixed to it an elastic arm 20, with a roller 21 in the end contiguous to the trolley-wheel 22 and in line with the shoe 18,

so that when the trolley has reached the point contiguous to this shoe the roller 21 will contact with the shoe, and thus transmit the electrical current through the trolley-pole, and by means of a connecting-wire, as shown 70 at 23, the current is transmitted through the electromagnet for a sufficient time to energize it and operate the carrier, as previously described.

In order to regulate the current taken 75 from the trolley-wire and give it the required character for passing through the electromagnet, I introduce one or more incandescent lamps in the circuit, as at 25. I have here shown also a fuse, as at 26, introduced 80 into the circuit to prevent accidents in case of a high-tension current.

In order to prevent the swinging of the leaves after they have dropped into position and to hold them in place, I have shown 85 springs, as 27, fixed at the lower part of the opening where the leaves are exposed, so that as the leaf drops by gravitation its lower edge swings past the ends of these springs sufficiently to be retained and prevent them from 90 further swinging. 28 represents rollers also located at the lower part of this opening and so placed that the edges of the leaves will move freely and without undue friction. As shown in the present case, these leaves may be formed 95 of heavy cardboard having a metal binding along each of their edges.

In order to remove or replace the cards or leaves, I have shown the perforations in the disk 4 as passing entirely through the disk, and upon the outer side of the disk is a turnable ring 4^a, which is unperforated except at one point. When this ring is turned, so that its unperforated surface registers with the holes in the disk, it forms a stop to prevent 105 the ends of the pins from being pushed through sufficiently to disengage the pins from the opposite disk 3; but if it is desired to remove either of the cards or leaves for any purpose the ring is turned until the hole in it coincides with the pin of the card to be 110 removed. The card is enough shorter than the distance between the disks to allow of a little play, and at the end contiguous to the disk 4 the space is sufficient to allow the card to be 115 moved in that direction, the pin passing into the hole in the ring until the pin which enters the disk 3 is clear of the hole. It can then be withdrawn and moved until the pin which enters the disk 4 can also be withdrawn and 120 the card removed. After replacing a card the ring is turned, so as to present an unperforated surface to all of the pins, and the cards are thus retained in place.

Having thus described my invention, what 125 I claim, and desire to secure by Letters Patent, is—

1. In a street or like indicator, cards having pins projecting from the ends of one side, disks mounted upon a horizontal revoluble 130

shaft and having holes around the periphery to receive the pins, a ring turnably mounted upon the outer face of one of the disks, said ring forming a stop against which the ends of the pins contact and having a hole made through it to register with any of the pins and allow a card to be moved to disengage it from the disks.

2. In a street or like indicator, a shaft revoluble disks mounted thereon and having perforations around the periphery, cards having a length less than the distance between the disks and pins projecting from the ends of the cards near one side so as to enter the perforations, a ring fitting and turnable against the outer face of one of the disks, said ring having a hole made through it adapted to register with the pin of any card whereby the latter may be introduced or removed.
3. In a street or like indicator, a shaft revoluble disks mounted thereon and having perforations in their peripheries, cards having a length less than the distance between the disks and pins projecting from the ends of the cards near one side so as to enter the perforations, a ring fitting and turnable against the outer face of one of the disks, said ring having a hole made through it adapted to register with the pin of any card whereby the latter may be introduced or removed, stops against which the upper edges of the cards contact during the forward movement of the cards, an intermittently-operating mechanism by which the cards are disengaged singly from the stops and allowed to swing about the pivots into a pendent position.
4. In a street or like indicator, a shaft revoluble disks mounted thereon and having per-

forations in their peripheries, cards having a length less than the distance between the disks and having pins projecting from their ends near one side and adapted to enter the perforations, a ring fitting and turnable against the outer face of one of the disks and having a hole adapted to register with the pin of any card whereby the latter may be introduced or removed, stops against which the cards contact in their revolution toward the front and after passing the vertical plane, intermittently-acting mechanism for disengaging the cards singly from the stops to allow them to swing into a pendent position, and spring-latches over which the lower edges of the cards pass and by which they are retained in place.

5. In a street or like indicator, a carrier comprising horizontally-journalized disks having holes around their peripheries, cards with pins entering and loosely turnable in the holes, mechanism for intermittently rotating the disks, stops against which the cards contact after passing the vertical plane from the top of the carrier, said cards being individually released by each forward movement of the carrier, elastic latches engaging the lower edges of the cards as they fall into a pendent position, and rollers against which these edges move when passing downward.

In testimony whereof I have hereunto set my hand in presence of two subscribing witnesses.

DEAN A. HOLZBERG.
